ANIMAL-SCRATCHING DEVICE

Fred L. Heese, Pender, Nebr., assignor to Automatic Equipment Manufacturing Company, Pender, Nebr., a corporation of Nebraska

Application June 7, 1944, Serial No. 539,103

2 Claims. (Cl. 119—157)

This invention relates to new and useful improvements in animal-scratching devices, and has for its primary object to provide, in a manner as hereinafter set forth, a device of this character which is adapted to deposit on an animal passing therethrough a mixture of oil and powder.

Another very important object of the invention is to provide a scratching device of the aforementioned character comprising unique means, operable by the animal, for thoroughly agitating and mixing the oil and powder prior to the application thereof to the animal.

Other objects of the invention are to provide an animal-scratching device of the character set forth which will be relatively simple in construction, strong, durable, highly efficient and reliable in operation, compact and which may be produced and installed at low cost.

All of the foregoing, and still further objects and advantages, of the invention will become apparent from a study of the following specification, taken in connection with the accompanying drawings wherein like characters of reference designate corresponding parts throughout the several views, and wherein:

Figure 1 is a view in front elevation of an animal-scratching device constructed in accordance with the present invention.

Figure 2 is a view in horizontal section through the device, taken substantially on the line 2—2 of Figure 1, looking downwardly, as indicated by the arrows.

Figure 3 is a view principally in vertical section through the upper portion of the device.

Referring now to the drawings in detail, it will be seen that the embodiment of the present invention which has been illustrated comprises a channel iron frame of substantially inverted U-shape, which is designated generally by the reference character 1. The frame 1 is adapted to be mounted on suitable supporting means such, for example, as a pair of posts fixed in the ground. The frame 1 includes a top member 2 and a pair of legs 3.

Operable vertically between the legs 3 of the frame 1 is a frame 4. An arcuate brush 5 is mounted in the frame 4. A vertical tube 6 is provided with a threaded lower end portion 7 which passes through the frame 4 and the brush 5. Nuts 8 on the threaded end portion 7 of the tube 6 secure said tube in position. It will be observed that the nuts 8 are located above the frame 4 and below the brush 5.

The tube 6 passes slidably through a vertical 55 in the details of construction may be resorted

guide bearing 9 which is provided therefor on the top member 2 of the frame 1. Fixed on the upper end of the tube 6 and communicating therewith is a container 10 for the reception of a mixture of oil and powder.

Mounted on the top 2 of the frame 1 is an arcuate bar 11. Depending from the arcuate bar 11 is a stationary screw shaft 12 which extends downwardly through the container 10 into the tube 6. The construction and arrangement is such that the tube 6 and the container 10 are capable of vertical movement independently of the stationary screw shaft 12. An opening 13 in the top 14 of the container 10 accommodates the stationary screw shaft 12.

Mounted on the stationary screw shaft 12 and operable in the container 10 is an agitator 15. The agitator 15 includes a hub or nut 16 which is threadedly mounted on the screw shaft 12. Spirally twisted blades 17 radiate from the nuts 16. In the embodiment shown, a ring 18 spaces the agitator 15 from the bottom 19 of the container 10, said ring having passages 20 therein establishing communication at all times between the tube 6 and said container.

In operation, the movable members of the device are normally in substantially the position shown in Figure 3 of the drawings. The container 10 may be loaded in any suitable manner to the desired level with the oil and powder in the correct proportions. When an animal passes through the device, the arcuate brush 5 engages its back and rides upwardly thereon. In this manner the tube 6 and the container 10 are elevated and the agitator 15 is forced upwardly on the stationary screw shaft 12. Thus, the agitator 15 is rapidly rotated for thoroughly stirring or mixing the oil and the powder in the container 10. With the mixture in this substantially liquid or semi-liquid state, it flows downwardly through the tube 6 and is deposited by gravity on the back of the animal passing through the device. After the animal has cleared the device and the members 5, 6 and 10 have returned to their lower position, the agitator 15 turns downwardly by gravity on the screw shaft 12 and comes to rest on the ring 18, ready for the next operation.

It is believed that the many advantages of an animal-scratching device constructed in accordance with the present invention will be readily understood, and although a preferred embodiment of said device is as illustrated and described, it is to be understood that changes

to which will fall within the scope of the invention as claimed.

What is claimed is:

1. An animal-scratching device comprising a frame, a brush, operable by an animal, slideable on said frame, a container, for the reception of a mixture, mounted on the brush and movable therewith, a stationary screw shaft mounted on the frame and projecting into the container, an agitator for the mixture threadedly mounted on the screw shaft and rotatable thereon in the container, upon vertical movement of the container relative to the screw shaft, and means for depositing the mixture from the container on the animal. 5 10 15

2. An animal-scratching device comprising a frame, a brush, operable by an animal, mounted for vertical sliding movement on said frame, a vertical tube on the brush, a container, for the reception of a mixture, mounted on the tube and communicating therewith, a stationary screw shaft on the frame projecting into the container and the tube, and an agitator for the mixture threadedly mounted on the screw shaft in the container and rotatable by said screw shaft upon vertical movement of the container relative thereto.

FRED L. HEESE.
